UNITED STATES PATENT OFFICE.

GEORGE A. PATTBERG, OF SAN LEANDRO, CALIFORNIA.

CAN OPENER.

1,420,666.

Specification of Letters Patent. Patented June 27, 1922.

Application filed April 16, 1921. Serial No. 461,888.

To all whom it may concern:

Be it known that I, GEORGE A. PATTBERG, a citizen of the United States, and a resident of the city of San Leandro, county of Alameda, State of California, have made a new and useful invention—to wit, Improvements in Can Openers; and I do hereby declare the following to be a full, clear, concise, and exact description of the same.

10 This invention relates particularly to can openers.

The principal object of this invention is to provide an improved can opener, similar for instance to devices for removing the closed 15 ends of containers or cans. An object of the invention resides in providing a tool that will remove the closed end of a can completely so as to restore substantially the full cross-sectional area of the container.

20 A further object consists in providing a can opener that will be simple and inexpensive to construct, superior, and positive and efficient in its operation. Other objects and advantages will appear as this description 25 progresses.

In this specification and the annexed drawings, the invention is illustrated in the form considered to be the best, but it is to be understood that the invention is not limited to such form, because it may be embodied 30 in other forms, and it is also to be understood that in and by the claims following the description, it is desired to cover the invention in whatsoever form it may be embodied.

35 In the accompanying one-sheet of drawings,—

Figure 1 represents a plan view of a can opener, constructed in accordance with my invention, applied in operative position to 40 a can.

Figure 2 represents a side elevation of Figure 1.

Figure 3 represents a similar side elevation of the can opener applied in the opposite 45 site position to that shown in Figure 2.

In detail the construction illustrated in the drawings includes a pair of substantially complementary handle members 1 and 2, cross-pivoted at 3 and provided with extended end portions 4 and 5 respectively. The handle members 1 and 2 are preferably cross-pivoted after the manner of a scissor or shear to take advantage of the obvious manner by which such tools are operated. Further-

more this construction lends itself to the 55 adaptation of my invention, in that the handle members 1 and 2, as compared with the ends 4 and 5, may be lengthened or shortened for increasing or diminishing the leverage required. It is well known that the 60 operation of opening a can is a task much dreaded by the housewife, for the reason, that the necessary strength and skill is lacking and at the same time the operation is besought with the danger of contacting the 65 tender skin of the hands with the rough, pointed and jagged ends of the can adjacent the point where the opening tool has been inserted. The device constructed in accordance with my invention severs the top from 70 the cylindrical body of the container so as to eliminate any or all projecting or rough, sharpened edges, thereby greatly minimizing the danger and risk attendant the opening of a can.

75 The end 4 of the handle member 1 on one side thereof is provided with a serrated projection 6 secured thereto by suitable rivets 7, welding or other equivalent fastening means. The projection 6 is preferably made 80 of a finer grained metal than that of the handles, as its function, to be later described, in the operation of the invention is to frictionally contact with the circumferential edge of the container. The end 5 of the other 85 handle member 2 is provided with an extended plate 8 pivotally joined thereto by a connecting pin 9. The pivot pin 9 is provided with a roller 14 mounted thereon substantially of the same thickness as the projection 6 and projecting from the underside of the plate 8 for the purpose to be hereinafter 90 described in detail. The underside of said plate 8 is provided with a cutting element or knife 10 projecting laterally therefrom in the same direction as the serrated projection 6 on the end 4 of the handle member 1. The knife 10 is fixedly secured in the plate 8 and has a threaded shaft 11 thereon projecting through the said plate and into a 95 threaded opening formed in the knobular projection 12 to rigidly bind said shaft and knife to said plate 8.

A suitable expansion spring 15 is secured around the pivot pin 3 and with an end 105 thereof fixed to each of the handle members 1 and 2 as at 16 and 17 respectively so as to normally spread the said handle members.

The handles 1 and 2 are shown as formed from sheet metal but it would be clearly within the purview of this invention to make them round or in any other perfect manner.

The invention operates in the following manner:

The operator grasps the handles 1 and 2 in one hand and with the fingers of the other grasps the knobular projection 12 and places the cutting element on the end of a cylindrical container near the circumferential edge thereof as at 20 and presses downwardly upon said knob 12 forcing the knife 10 through the top of the can into the interior thereof. During this operation, the roller 14 on the end 5 of the handle 2 has been placed against the end circumference of the can and the serrated projection 6 on the end 4 of the other handle 1 likewise placed in frictional contact with the circumferential edge of the can. The operator would then permit the handles to be separated through the action of the spring 15 thus spreading the plate 8 from the serrated projection in which position with the free hand, the operator would steady the upper part of the can and again, draw the handles 1 and 2 together against the tension of the spring 15. The action of closing the handles 1 and 2 tends to draw the knife 10 around the circumference of the end of the can severing the end from the sides of the cylindrical container for a distance proportionate with the length of the stroke resulting from the drawing together of the handles 1 and 2. The handles 1 and 2 would next be allowed to spread in an obvious manner and the closing operation repeated until the cutting knife has been moved around the circumference of the can to sever the top from the edges thereof and to permit its removal. The cutting action is such that the end of the can severed from the cylindrical side walls is within the body thereof and not ex-

posed so that the hands of the operator could easily come in contact therewith.

Having thus described this invention, what I claim and desire to secure by Letters Patent is:

50

1. A device such as described comprising a pair of opposed handle members pivoted together; a cutting element projecting laterally from the face of the end of one of said members and a serrated projection on the end of the other member.

2. A device such as described comprising a pair of opposed handle members pivoted together; a plate pivotally mounted on the end of one of said members and having a cutting element projecting laterally from the face thereof and a serrated projection on same end of the other member.

3. A can opener, such as described, comprising a pair of opposed handle members pivoted together; an end of one of said members having a serrated projection thereon adapted to frictionally engage the circumference of a can to be opened and the end of the other member having a cutting element pivotally mounted thereon and projecting laterally from the face thereof and adapted to be inserted through the end of said can.

4. A can opener, such as described, comprising a pair of opposed handle members pivoted together; an end of one of said members having a serrated projection thereon adapted to frictionally engage the circumference of a can to be opened; a plate pivotally mounted on the end of the other member and a cutting element projecting laterally from the face thereof and adapted to be inserted through the end of said can.

In testimony whereof, I have hereunto set my hand at San Francisco, California, this 5th day of April, 1921.

GEORGE A. PATTBERG.

In presence of—

LINCOLN V. JOHNSON.
